United States Patent Office

Des. 204,596
Patented May 3, 1966

204,596

INSOLE

Arthur H. Anson, 805 N. 26th St., Allentown, Pa.

Filed Mar. 16, 1965, Ser. No. 84,300

Term of patent 14 years

(Cl. D7—5)

FIG. 1

FIG. 2

FIG. 3

FIG. 5

FIG. 4

FIGURE 1 is a top perspective view of an insole, showing my new design;

I claim:

The ornamental design for an insole, substantially as shown.
